UNITED STATES PATENT OFFICE

106,761

DESIGN FOR A BUTTON OR SIMILAR ARTICLE

Thomas J. Flynn and Charles G. McClintock,
Detroit, Mich.

Application August 9, 1937, Serial No. 70,938

Term of patent 7 years

To all whom it may concern:

Be it known that we, Thomas J. Flynn and Charles G. McClintock, citizens of the United States and residents of Detroit, Wayne County, State of Michigan, have invented a new, original, and ornamental Design for a Button or Similar Article, of which the following is a specification, reference being had to the accompanying drawing, forming a part thereof.

We claim:

The ornamental design for a button or similar article substantially as shown.

THOMAS J. FLYNN.
CHARLES G. McCLINTOCK.
